UNITED STATES PATENT OFFICE.

HARRY G. DEAN, OF CLEVELAND, OHIO.

DESIGN FOR A SHOE.

45,412.

Specification for Design.

Patented Mar. 17, 1914.

Application filed April 18, 1913. Serial No. 762,122. Term of patent 7 years.

To all whom it may concern:

Be it known that I, HARRY G. DEAN, a citizen of the United States, residing in Cleveland, in the county of Cuyahoga and State of Ohio, have invented a new, original, and ornamental Design for Shoes, of which the following is a specification, reference being had to the accompanying drawings, forming part hereof.

The figure is a perspective view of an

article of ladies' footwear showing my new design.

I claim:

The ornamental design for a shoe, as shown.

HARRY G. DEAN.
